UNITED STATES PATENT OFFICE.

FREDERICK LARSON, OF CHELSEA, MASSACHUSETTS.

DOOR-HANGER.

SPECIFICATION forming part of Letters Patent No. 629,165, dated July 18, 1899.

Application filed March 23, 1899. Serial No. 710,164. (No model.)

To all whom it may concern:

Be it known that I, FREDERICK LARSON, of Chelsea, county of Middlesex, State of Massachusetts, have invented an Improvement in 5 Door-Hangings, of which the following description, in connection with the accompanying drawings, is a specification, like letters on the drawings representing like parts.

This invention has for its object to hang in 10 a novel manner sliding doors, provision being made to adjust the door as may be required.

My invention is more especially devised for hanging sliding doors in bookcases, cabinets, pantries, &c., where one door or sash is to 15 slide past another; but my invention is not limited to such use, as it may be employed in any other position desired without departing from my invention.

Figure 1, in broken detail, shows one door 20 and part of another door suspended by my improved hangers on my improved roller-frame. Fig. 2 is a partial section through the roller-frame, both doors being pushed fully to one side of the line of section to show 25 their edges, said figure also showing a part, say, of the "header" of a bookcase. Fig. 3 is a broken-out side elevation of one of the hangers. Fig. 4 is a view of the hanger shown in Fig. 3, looking at it from the right. Fig. 5 shows the toothed plate in two positions.

My invention is especially designed to support sliding doors and sashes, as stated, for bookcases, pantries, cabinets, &c., where 35 doors and sashes are made to slide one past the other to gain access to the interior of the space closed by the door or sash. For this purpose I have devised a special roller-frame, it in practice being fitted into the interior of 40 the cabinet, bookcase, or other place where it is to be used. This roller-frame is composed, preferably, of connected side pieces *a*, *c*, each having a track, as *a*', *c*', the said side pieces being herein represented as composed of wood 45 and united together at their upper ends by a strip *b*, shown as tongue-and-grooved. The side pieces and strip *b* make a roller-frame. At the interior of this roller-frame I apply a center piece *d*, having at its opposite edges 50 suitable tracks, (see Fig. 2,) which stand normally at the level of the tracks *a*', *c*'. This center piece is represented as divided at *d*'

(see Fig. 1) diagonally in the direction of its length, and said divided diagonal ends are united together and to the strip *b* by a suitable screw, as *d*², and other suitable screws *d*³ may be used at any point in the length of the center piece to thereby confine the center piece properly with relation to the roller-frame. As herein shown, the strip *b* is provided with a groove to receive the narrower edge of the center piece. (See Fig. 2.)

e represents a door or sash and *e*' a second door or sash. Each door has a suitable hanger, and each hanger has suitable rollers, to be described, which run upon the tracks of the roller frame. Each door or sash at its vertical edge, near its upper end, has attached to it by a suitable screw, as *f*, a toothed plate *f*', said plate having a suitable elongated slot or opening *f*² to receive a screw *f*³, said screw being extended through an elongated slot *g* in an angle-iron *g*', forming the base of the hanger, said angle-iron having rising from it a suitable ear *g*², which sustains a suitable 75 axle *g*³, said axle receiving upon it at each side of said ear a roller, as *g*⁴ *g*⁵. These rollers run on the tracks referred to, one roller running on one track of each of said side pieces *c*, while the other two rollers run on 80 the two tracks carried by the center piece. The angle-iron has at its depending lower end a series of teeth, as *g*⁶, which engage the teeth *f*⁴ of the toothed plate *f*'. The inner horizontal ends of the angle-irons are secured to 85 the upper edge of the top by suitable screws *h*. (Represented in Fig. 1, where the door or sash is shown as broken out.)

The diameter of the rolls is but little short of the distance from the surface of the tracks 90 on which they run and the upper edge *h*' of the space within which the rollers travel, so that there will be no jumping up and down of the rollers on the track.

To position the door or sash exactly with relation to the roller-frame, the screw *f*³ may be loosened and the angle-iron be raised or lowered with relation to the door at its top, the slot *g* permitting such movement, and the teeth *g*⁶ of the angle-iron may be made to re- 95 engage the teeth of the toothed plate *f*' and the screw *f*³ to be again turned into place.

In this my invention it will be obvious that the door or sash cannot get off the track, and

the lower end of the door or sash may be adapted to always clear as much as desired the woodwork of the cabinet, bookcase, or china-closet where the door or sash is used, and in this way the door or sash may always be held in condition to be easily and readily moved over the track, and it cannot bind anywhere.

Having described my invention, what I claim as new, and desire to secure by Letters to Patent, is—

1. A roller-frame consisting of side pieces provided with inturned tracks, and a center piece having tracks, substantially as described.
- 15 2. A roller-frame consisting of side pieces provided with inturned tracks, and a detachable center piece having outturned tracks, substantially as described.
3. A roller-frame consisting of side pieces 20 provided with inturned tracks, a detachable divisible center piece on said roller-frame, substantially as described.
4. A toothed plate slotted at f^2 and adapted to be fixed to the edge of a door; combined

with a roller-hanger made as an angle-bar carrying a roller, said bar being adapted to be fitted and secured to the edge and top of a door, one end of said bar being provided with teeth to engage the teeth of said slotted plate, said angle-bar having a slot to receive the adjusting-screw used to confine the toothed end of said bar in engagement with the teeth of the slotted plate, substantially as described.

5. A roller-frame consisting of side pieces provided with inturned tracks, and a detachable center piece having outturned tracks to thereby provide a plurality of ways, combined with a plurality of doors or sashes, each having a plurality of rollers running on each pair of tracks of the said roller-frame to operate 40 substantially as described.

In testimony whereof I have signed my name to this specification in the presence of two subscribing witnesses.

FRED. LARSON.
